UNITED STATES PATENT OFFICE

2,642,203

CAN OPENER

Frank G. Seemiller, Philadelphia, Pa.

Application April 30, 1952, Serial No. 284,111

3 Claims. (Cl. 220—48)

1

The object of my invention is to devise a novel can opener which may be permanently attached to the top of a can or container to form a unit of structure therewith, and after use it can be discarded with the opened can.

The can opener has pivot connections with the can and is provided at its ends with piercing points, whereby when the can opener is turned in one direction on its pivots a pouring opening is formed in the top of the can, and if desired a vent opening can be formed by turning an integral lever portion on its pivotal connection with the body portion of the can.

A further object of the invention is to form the can opener from sheet material by a stamping operation with maximum economy in manufacture, and with an integral lever like portion flexibly connected with the body portion of the opener for causing the turning of one of the piercing points on the body portion to penetrate the can top.

With the foregoing and other objects in view as will hereinafter clearly appear, my invention comprehends a novel can opener fixed to the top or end of a can or container in such a manner as to form a pivotal connection on which the opener is turned to form a pouring opening and if desired a vent opening in a top or end of a can or container.

For the purpose of illustrating the invention, I have shown in the accompanying drawings preferred embodiments of it which I have found in practice to give satisfactory and reliable results. It is, however, to be understood that changes and modifications can be made within the scope of the appended claims.

Figure 1 is a perspective view of a can and my novel opener in pivoted connection with the can.

Figure 2 is a section on line 2—2 of Figure 1, showing more particularly the operation of the piercing points.

Figure 3 is a perspective view of a portion of a can and opener, showing more particularly the manner in which the lever has a hinge connection with the body portion of the opener.

Figure 4 is a top plan view of a can and the opener.

Figure 5 is a top plan view of a modified form in which the lever for the vent opening is omitted.

Figure 6 is a section on line 6—6 of Figure 5.

Figure 7 is a perspective view showing how the opener can be separated from the can after the pouring opening has been formed.

Figure 8 is a plan view of another embodiment.

Similar numerals of reference indicate corresponding parts.

Referring to the drawings:

5 I designates a can opener embodying my invention which can be formed from sheet material by a stamping operation. The side walls of the body portion at one end converge to form a piercing point 2, and converge at the opposite end to form a smaller piercing point 3. In rear of the piercing point 2, side flanges or ears are formed as at 4 and these flanges are secured to the top or end of a can or container by spot or shot welding, solder or rivets or in other proper manner to provide pivot points for the turning movement of the can opener as shown at 5. To facilitate such operation, slits 6 are preferably provided. The larger point 2 is for forming the pouring opening, and the smaller point 3 is for forming the vent opening.

10 20 Near the end carrying the piercing point 3 for the vent opening of the can, the body portion of the opener is slit to form a lever like portion 7 the free end of which is bent upwardly to facilitate grasping it and the connection 8 with the body portion forms a hinge for turning movement of the lever 7 when the piercing point 3 is to be used to form a vent opening in the can. The body portion may be bent upwardly as at 9 to facilitate the operator in raising the opener to form the pouring opening. The can or container is indicated at 10 and is of any conventional design or formation.

25 In some cases the means for forming the vent opening may be dispensed with as shown in Figures 5 and 6. The body portion has at one end a piercing point 11 and side flanges 12 the same as in the other figures of the drawings which are fixed to the can top to form pivots for turning movement of the opener. The end opposite to the piercing point is slightly bent upwardly as at 13 to facilitate the taking hold of the opener. In the operation, the opener is raised upwardly on its pivots and the lever 7 turned to form the vent opening and then further raised to form the pouring opening. The air vent lever can be broken off or bent to its original position so that when the opener is moved to a horizontal position with the can top the vent opening and also the pouring opening are covered. The opener can be separated from its flanges as in Figure 7, if desired.

30 35 40 45 50 55 In order to use lighter gauge metal or other sheet material, the body portion is deformed to provide reinforcing grooves or ridges of any desired character.

The body portion of the can opener may be pivotally mounted on top of the can in a number of different ways, and in Figure 8, I have shown the body portion in rear of the piercing point for forming the pouring opening in the can as provided with an aperture 14 to receive a pivot rod 15, the ends of which are preferably somewhat flattened and permanently fixed to the body portion of the can by welding or soldering.

In all of the embodiments of the invention as herein shown, the can opener, when pivotally fixed to the can, is within the conventional rim of the can so that it does not interfere in any manner with the stacking of the cans.

When the vent opening is to be made, the lever and piercing point 3 are preferably bent to bring the piercing point at substantially right angle to the body portion of the can opener, as shown in Figure 3, and then a downward pressure on the body portion forces the piercing point into the can to form the vent opening.

Having thus described my invention, what I claim as new and desire to secure by Letters Patent is:

1. The combination with a can top, of an 25
opener comprising an elongated metal strip permanently pivoted to the can top near one end of the strip and having at opposite ends piercing points, and one of said piercing points having a hinge connection with the body portion of the strip and having a lever arm formed from the strip to effect its pivotal movement relatively to the body portion of the strip.

2. A can opener, comprising an elongated metal strip having at one end a piercing point for forming a pouring opening in a can, having at its opposite end a piercing point for forming a vent opening in a can, the point for forming the vent opening being bendable at an angle to the body portion, and said body portion having in rear of the point for forming the pouring opening pivot forming means connectible with an end of a can.

3. A can opener, comprising an elongated strip having side edges at one end converging to form a piercing point for a pouring opening in a can, having opposite side edges at the opposite end converging to form a piercing point for a vent opening in the can, and having pivot forming means for the piercing point for the pouring opening, the piercing point for the vent opening having a hinge connection with the body portion of the strip, and the strip having a slit extending from the hinge connection and forming a lever arm to effect pivotal movement of the vent forming piercing point relatively to the body portion of the strip.

FRANK G. SEEMULLER.
